(57) CLAIM

The ornamental design for a shoe covering strap, as shown and described.

DESCRIPTION

FIG. 1 is a front view of a shoe covering strap showing my new design;

FIG. 2 is a back view thereof;

FIG. 3 is a side view thereof;

FIG. 4 is a top view thereof;

FIG. 5 is a bottom view thereof; and,

FIG. 6 is a perspective view thereof.

All surfaces not shown form no part of the claimed design.
